UNITED STATES PATENT OFFICE

ALBERT ALEXANDRE AUGUSTIN DARCHE, OF ALGIERS, FRANCE

DEVICE INSURING AN INTENSE STIRRING UP IN EXPLOSION MOTORS PROVIDED WITH
TWO LATERAL VALVE BOXES (T HEADS)

Application filed July 18, 1928, Serial No. 293,534, and in France July 29, 1927.

According to a commonly used arrangement, the explosion motors are provided with a combustion-chamber comprising two lateral valve-boxes, one of them containing the admission-valve and the other the exhaust-valve.

From the mechanical point of view, this arrangement is favourable for multi-cylinder motors, because it permits the employment of 10 large valves and of approached cylinders. Furthermore this arrangement lends itself easily to the placing of pipes and to the control of the valves.

The spark-plug is placed sometimes above 15 the admission-valve. In some cases the spark-plug is arranged in the center of the combustion-chamber.

From the point of view of obtaining an 20 explosion wave and a high thermo-dynamic efficiency with aid of a high compression, these two arrangements are not recommendable. The worse arrangement is the one comprising a spark-plug above the admission-valve.

25 The utilization of a T-like combustion-chamber can be improved very essentially by the employment of the following arrangements constituting features of the present invention.

30 According to the invention, the free space existing usually between the cylinder and the piston when the latter is at the end of its instroke or in upper dead center position, is reduced as far as possible from the mechanical point of view. In this way two chambers 35 of combustion are obtained, which are practically distinct from each other, each chamber having a very small volume and provided with a distinct spark-plug. In this manner, hence, two combustion-chambers permit an essential diminution of the passage of the flame in each chamber, which condition is favorable from the point of view of limitation of the deflagration and its risk.

40 Toward the end of its compression-stroke the piston progressively obturates the communication existing between the cylinder and each valve-chamber, and hence the gases still remaining in the cylinder are forced with 45 great speed into said valve chamber and

therefore the gaseous mass is agitated and stirred with violence.

The effect of this stirring-up action is very important because it is coincident with the occurrence of ignition and facilitates a rapid 55 propagation of the flame.

The following outstroke of the piston causes an inverse flow of the gases, at high speed, from the chambers into the cylinder across limited sections, so that there is continued 60 turbulence of the gases and their combustion eventually completed, and the gaseous film between the cylinder head and the inner end of the piston being instantaneously burned.

65 The shock of the ignited gases arriving from the opposite directions from the valve chambers is also a favorable factor in its action on the piston.

The accompanying drawing is a vertical 70 sectional view of a cylinder provided with a combustion chamber and valve chambers in accordance with this invention.

P represents the piston prolonged in its upper part so as to obturate progressively 75 toward the end of its ascending stroke the channels which establish communication between the cylinder and the valve-chambers A, A₁. The valve chambers are provided with spark-plugs B, B₁, arranged in covers or the like which are removable to permit inspection 80 of the valves.

S and S₁ are the admission- and exhaust-valves respectively.

85 In case of transformation of existing motors by simply replacing the piston, the suppression, nearly complete, of the volume present between the summit of the piston and the bottom of the cylinder is followed by an increased compression attaining eventually a 90 too high value. In order to reduce the same it will suffice to introduce, by throttling the admission, or provide a volume of cylinder swept by the piston at limited pressure, which corresponds to a lesser (pressure) volume at 95 the usual pressure, obtained after a certain stroke of the piston at the time of compression. Besides, the thermo-dynamically advantageous prolonged expansion during the motive stroke of the piston will be secured. 100

This method constituting the features of the French patent for "Explosion motor with over-vacuum and prolonged expansion", filed 21st of March, 1927, will be combined, in all cases, very advantageously with the features of the present invention.

The figure of the drawing being only a diagrammatic view, its relative dimensions are only approximately included.

10 The invention permits within its scope manifold modifications without departing from the essence of the appended claim.

What I claim, is:

In a four cycle internal combustion engine, a T-shaped cylinder head, provided with 15 two lateral valve chambers, the one containing the admission valve, the other the exhaust valve, each valve chamber being entirely lateral to the cylinder and at a level with the 20 top of the piston when the latter is at the end of its in-stroke, the upper surfaces of said valve chambers being in the same plane as that of the cylinder, each of the valve chambers communicating with the cylinder by a 25 lateral passage arranged practically at right angles to the axis of the cylinder and the free space remaining at the end of the compression stroke, between the upper end of the cylinder and that of the piston, being substantially 30 eliminated to isolate the two valve chambers and cause them to form two combustion chambers practically distinct from each other, each said chamber having its own ignition means, all arranged so that the piston towards 35 the end of its compression stroke progressively closes the lateral passage between the cylinder and each valve chamber, and hence causes the passage therethrough at increased speed to the gases remaining in the cylinder, and 40 therefore also causes an active turbulence in each combustion chamber at the moment of ignition while at the return, at high speed, into the cylinder of the gases at high temperature in a direction practically parallel to the 45 end of the piston, the violent agitation produced by the meeting of the opposite jets from each chamber completes almost instantaneously the combustion of the gases so that the engine permits the use of mixtures which are 50 less rich than normally required but whose combustion is nevertheless extremely rapid.

In witness whereof I affix my signature.

ALBERT ALEXANDRE AUGUSTIN DARCHE.
